UNITED STATES PATENT OFFICE.

ROBERT S. PERRY, OF CAVE SPRING, GEORGIA.

ART OF PAINTING POROUS SURFACES.

1,239,953.

Specification of Letters Patent. Patented Sept. 11, 1917.

No Drawing.

Application filed January 20, 1917. Serial No. 143,486.

To all whom it may concern:

Be it known that I, ROBERT S. PERRY, of Cave Spring, in the county of Floyd and State of Georgia, have invented a new and 5 useful Improvement in the Art of Painting Porous Surfaces, whereof the following is a specification.

In using the term "porous" as indicative of the surfaces to the painting of which my 10 invention is addressed, I mean surfaces having porosity of the character manifested by wood, textile fabric, plaster, concrete, mortar, unglazed brick and unglazed tile, as typical instances, it being noted that in all 15 of these the inherent porosity of the material is of such a character as to manifest itself in capillary attraction for a liquid, such as water.

As the art has heretofore been practised, 20 it is usual, in painting surfaces of this character for protective or decorative purposes, first to apply upon the surface a priming coat or coats, and subsequently to apply a finishing coat or coats, the priming coat 25 consisting usually of a vehicle, such as linseed oil, carrying finely divided material which may have some pigmentary value. Such priming material was constituted with special reference to penetrative, adhesive, 30 moisture-excluding, and gas-excluding properties, and to the further desideratum that its surface should present a proper ground for the finishing coat or coats.

The character of these latter coats is 35 constituted with special reference to certain surface qualities, some of which are physical, such as, resistance to weather, capacity to shed moisture, and the like, while others are mainly decorative.

40 The desiderata of a priming coat or coats may generally be stated as follows:

First, sealing quality, or substantial imperviousness to moisture, air, or other forms of liquid or gas.

45 Second, elasticity or ductility, in order that the coating may reasonably conform to the conditions of expansion or contraction of the surface.

Third, adhesive quality, including the 50 ability to penetrate the cellular surface, and thus minimize the tendency of the priming to peal off therefrom.

Fourth, opaqueness, or substantial concealment of the surface, in order to permit 55 the desired decorative or artistic effects of the final coats.

Fifth, substantial freedom from internal strains which would tend to shorten the life of the entire system of coating.

Sixth, uniformity throughout the body 60 of the priming.

Seventh, advantageous surface conditions for the finishing coat or coats, in that the surface to which they are to be applied shall be uniform and yet not so hard and glossy 65 as to render the finishing coats liable to peel off.

Much effort has been applied to obtaining all these qualities in a satisfactory degree in a priming coating, but it has been 70 found that they all fall short of the full measure desired in each respect.

First, they are not entirely impervious and do not seal the surface, even when initially applied, and they tend to become 75 more penetrable and to diminish in sealing quality with age.

Second, while they may have considerable elasticity or ductility when first applied, these qualities progressively diminish with 80 age, and may even ultimately disappear.

Third, while their initial penetration and adhesive qualities are manifest when first applied, they almost invariably contain organic compounds which tend to deteriorate, 85 and hence the danger of peeling or chalking increases.

Fourth, while they may possess opaqueness to a certain degree, yet by reason of the small quantity of pigment, which they 90 usually carry, this is somewhat impaired by the nature of the vehicle, which is usually translucent or nearly so.

Fifth, while they may, when first applied, be substantially free from internal 95 strains, such strains progressively manifest themselves with age, and produce cracks or checking.

Sixth, the formulæ for their composition are complex and the material is applied by 100 human agency, so that the personal element enters largely into their application, both as regards economy of material and uniformity of body.

Seventh, their surface condition, considered with reference to the application of the finishing coat or coats, varies with varying conditions of the surface upon which they have been applied, and thus tends to lack of uniformity as a preliminary surface or 110 "ground".

I have discovered that an initial coating

(which may be termed by analogy, a priming) of peculiar character can be applied to surfaces of the general class mentioned, under conditions which give it a specific value 5 and novel character both as a priming, *per se*, and also for the superimposition of the finishing coat or coats, the total result being that while the latter may be applied in the usual way and may have any desired 10 decorative or protective character, the priming will be substantially free from the defects above pointed out, and consequently the paint coating, as an entirety, will possess novel and valuable characteristics.

15 To this end I proceed as follows:

I first coat the surface by hot spraying metallic lead thereon to form a film, preferably employing for this purpose the apparatus and process now known to the arts 20 under the name of the Schoop metal spray process.

The lead film thus applied presents the following characteristics, *viz*: It penetrates the structure of the material to a sufficient 25 degree to engage physically in the pores thereof; it adheres thereto with great firmness; its coherence is such that it may be considered as substantially continuous; its uniformity and physical dimensions are 30 readily controllable; and it presents an external surface which is mat, or uniformly dull, owing to the existence of very minute but uniformly distributed interstitial cavities. Although the lead surface thus formed 35 may not properly be termed porous, in a strict sense, and although its cavities are not necessarily related in position or extent to the pores of the underlying material, yet they afford results which may be said to be 40 comparable to those of a slightly porous surface, in that they afford an almost ideal "ground" for the finishing coat or coats.

I have found that by the use of the primary coating characteristic of my invention, 45 all the seven qualities above referred to as desirable, are secured to an extent to which no primings, known to the painters' art as heretofore practised, have attained.

Incidentally, there are economic features, 50 such as the reduction of the labor of appli-

cation, and also the avoidance of waste, which are in themselves important factors, but these may be viewed as subordinate in comparison with the direct advantages due to the use of the invention, the essential 55 principle of the latter residing in my discovery of the peculiar behavior of a metallic lead priming film, having the characteristics above set forth.

I have used the term "lead", as indicating 60 the material which I employ, without, however, intending to restrict my invention to pure metallic lead as such, but although the presence of other metallic ingredients may be tolerated, the metallic coating should 65 comprise a substantial percentage of lead.

Having thus described my invention, I desire to state that I do not claim the process of applying hot sprayed metal to a surface, whether porous or otherwise, nor do I claim 70 the application of a coat or coats of paint upon a metallic surface.

My invention resides in the discovery that a film composed substantially of lead and applied to a porous surface in the manner 75 set forth, coöperates in a peculiar and novel manner, for priming purposes, both with said surface and also with the superimposed finishing layer or layers, and consequently enhances the aggregate value of the paint 80 system thus built up.

I claim:

As an improvement in the art of painting surfaces of porous material, the hereinbefore described process, which consists in first hot 85 spraying the surface with finely divided lead, to form a penetrant, adhesive, and coherent film, with a mat external surface; and subsequently applying upon the external surface of the film a coating of vehicle- 90 carried pigment, substantially as set forth.

In testimony whereof, I have hereunto signed my name at New York city, in the county and State of New York, this 17th day of January, 1917.

ROBERT S. PERRY.
